US00D979730S

(12) **United States Design Patent** (10) Patent No.: **US D979,730 S**
(45) Date of Patent: **** Feb. 28, 2023**

(54) **AIR CLEANING DEVICE**

(71) Applicant: **Zehnder Group International AG**,
Gränichen (CH)

(72) Inventors: **Janne Paiho**, Motala (SE); **Magnus Bladh**, Stockholm (SE)

(73) Assignee: **ZEHNDER GROUP INTERNATIONAL AG**, Gränichen (CH)

(**) Term: **15 Years**

(21) Appl. No.: **35/510,630**

(22) Filed: **Sep. 24, 2020**

(80) **Hague Agreement Data**

Int. Filing Date: **Sep. 24, 2020**

Int. Reg. No.: **DM/210853**

Int. Reg. Date: **Sep. 24, 2020**

Int. Reg. Pub. Date: **Oct. 30, 2020**

(51) **LOC (14) Cl.** 23-04

(52) **U.S. Cl.**

USPC **D23/364**

(58) **Field of Classification Search**

USPC D23/355, 356, 359, 364, 370, 386

CPC B01D 46/00; B01D 46/0002; A61L 9/00

See application file for complete search history.
